RADIO BROADCAST SELECTING AND DISTRIBUTING SYSTEM

Filed Feb. 29, 1924

Sends heterodyning wave over line

Inventor

Edward E. Clement

UNITED STATES PATENT OFFICE.

EDWARD E. CLEMENT, OF WASHINGTON, DISTRICT OF COLUMBIA. ASSIGNOR TO EDWARD F. COLLADAY, OF WASHINGTON, DISTRICT OF COLUMBIA.

RADIO BROADCAST SELECTING AND DISTRIBUTING SYSTEM.

Application filed February 29, 1924. Serial No. 695,993.

To all whom it may concern:

Be it known that I, EDWARD E. CLEMENT, a citizen of the United States, residing at Washington, in the District of Columbia, have invented certain new and useful Improvements in Radio Broadcast Selecting and Distributing Systems, of which the following is a specification, reference being had therein to the accompanying drawing.

10 My invention relates to systems for radio broadcast distribution and has for its object to render it possible for subscribers with a very simple type of receiving apparatus to be able to select with certainty and receive 15 with ample power from any distant station within the range of the present high powered long range receivers, such as the super-heterodyne. Other objects will sufficiently appear hereinafter.

20 I attain my object by providing each subscriber to the system with a receiving antenna and tuned secondary circuit as usual, and I supply each subscriber from a central station with unmodulated pulsating current 25 at a frequency suitable to heterodyne with the carrier current received from any particular or desired distant station. In order to be able to do this, I install at a central station a plurality of oscillators tuned to 30 different frequencies, and I provide the output terminals of these oscillator circuits with proper switching terminals, such as jacks or the like, so that they can be interconnected with the subscriber's wired lines. In 35 the connecting circuits, which may be ordinary cord circuits with terminal plugs, provided at the central office for connecting oscillators to the subscriber's lines, I provide detector tubes, which rectify the oscillator currents, and since their plate circuits are connected to the lines, they supply the latter with unmodulated pulsating 40 high frequency heterodyning currents. These currents are taken in at the subscriber's station in one side of either a differential circuit or in a differential receiver and therein combined with the modulated 45 radio currents received over the antenna circuit, to produce locally an amplified modulated asymmetric beat wave, which is capable of being received on an ordinary radio telephone receiver, with or without the usual bridging phone condenser. Various types 50 of local heterodyning circuit or instrument 55 may be employed, the invention residing particularly in the supply and transmission from the central station of unmodulated oscillator current at different frequencies, to enable the subscriber to make selection by heterodyning without the trouble of elaborate apparatus or tuning at his substation. An ancillary but very important feature of the invention is the furnishing of unmodulated pulsating current for heterodyning whereby the beat wave will be an asymmetric modulated wave, capable of being received in an ordinary radio telephone receiver, when properly connected, without further detection, thus obviating the necessity for detectors at the subscriber's stations. Furthermore, the type of current thus supplied in the line circuits is suitable for communication back and forth between the subscribers and the operators.

55 My invention is illustrated in the accompanying drawings in which—

Fig. 1 is a diagram showing a central station and a subscriber's station and connecting circuits for the same, together with oscillators at the central station.

60 Figs. 2 and 3 show subscribers' receivers.

Referring to the drawing, Fig. 1, C is a central station and S is a subscriber's station. At the former I locate oscillators O, O', O², etc., having their circuits connected to switching terminals J, J', J², etc., whereby they may be interconnected with the switching terminals J³ of subscriber's lines. The switching terminals in the drawings are shown as jacks, and the connecting means as plug cord circuits A and B. The cord A has a plug P and a plug P' connected by conductors 1, 2, 3, 4, 1 and 3 constituting the input or grid circuit of a tube conductor D, the plate or output circuit of which is connected through the plug P' to line wires 5—6 leading to the subscriber's station.

65 The service rendered by the central station C to its subscribers includes a certain range in point of distance, and also a certain range in point of wave lengths through which selections can be made under the supervision of the operators. For example, from 200 to 600 meters is the usual range of short wave lengths used in ordinary telephone broadcasting. The wave lengths supplied by the oscillators O, O', O² should be such that they will form a heterodyning scale with the broadcasting wave lengths of the stations listed and intended to be re- 110

ceived by the subscriber. Each subscriber will have to do his own tuning as at present, so far as his antenna circuit and local receiving circuit is concerned, but this is simple when the instrument is calibrated and standardized, involving merely the setting of the variable condensers or equivalent apparatus to readings taken from a table. Beyond this the subscriber has nothing to do except to ask central for the station wanted. He is thereupon supplied with unmodulated oscillator current of such a frequency that the difference between it and the frequency of the waves used by the station wanted, will be the uniform beat frequency to which all the subscriber's instruments are standardized.

The operator is provided in each cord circuit with a key K by means of which she can include her headset H in the plate circuit and therefore in series with the line and the subscriber's instrument. It is possible to make this a bridging arrangement by using a bridging battery in the plate circuit, with radio and audio choke coils in the battery bridge. The plate-filament branch of the tube, the subscriber's circuit, and any temporary connection of the operator's set would then all be in parallel with the battery, and the subscriber and the operator can talk back and forth on the high frequency high potential pulsating plate current. The same is true of the series arrangement.

Referring to Fig. 2 I have shown therein a type of Fessenden receiver adapted to respond to heterodyne or beat wave effects produced in the manner thus described. In Fig. 3, I show an equivalent arrangement of coils, in which a single wound radio telephone receiver may be employed. In either case, the energy conveyed over the wired circuit by the unmodulated oscillator current is imparted to the beat wave carrier, and thereby to the audio modulations, so as to produce an amplification sufficient for ordinary headphone purposes. If further amplification be desired, battery current being supplied over the line circuit from the central office to the subscriber's station, as usual in modern telephone systems, may be used in a local audio amplified circuit, with

a tube detector, which however I do not claim herein, as the same forms part of the subject matter of a separate application. 55

I claim:

1. In a system of radio broadcast distribution, a central station and subscribers' stations and wired line circuits interconnecting them, means at a subscriber's station for receiving modulated radio frequency carrier waves, means at the central station for supplying the subscriber's station over said wired line with unmodulated periodic current at such a frequency as will heterodyne 65 with the modulated waves received at the subscriber's station, to produce a standard modulated beat wave in the subscriber's receiver.

2. In a system of radio broadcast distribution, a central station and subscribers' stations and wired line circuits interconnecting them, means at the subscriber's station for receiving ether waves, means at the central station for generating unmodulated 70 periodic current, switching means for connecting said central office generators interchangeably with said subscriber's wired line circuits, and audio receivers at the subscriber's station responsive to modulations 75 carried on the standard beat waves due to the composition of the modulated and the unmodulated waves received through the ether and through the line circuits respectively. 85

3. In a system of radio broadcast distribution, a central station and subscribers' stations and wired line circuits interconnecting them, an oscillator circuit at the central office, switching terminals therefor, switching terminals for the line circuits, and intermediate connecting circuits with terminals adapted to operate interchangeably with said switching terminals, each connecting circuit including a detector whereby the oscillator current is rectified and transmitted over the subscriber's line as a high frequency unmodulated high potential pulsating current, adapted to combine with received radio carrier waves to produce an 95 100 asymmetric modulated beat wave.

In testimony whereof I hereunto affix my signature.

EDWARD E. CLEMENT.
